(57) **CLAIM**

The ornamental design for a shallow water anchor, as shown and described.

DESCRIPTION

FIG. 1 is a rear end elevation view of a shallow water anchor;

FIG. 2 is a front end elevation view thereof;

FIG. 3 is a bottom plan view thereof;

FIG. 4 is a top plan view thereof; and,

FIG. 5 is a right side elevation view thereof, the left side being a mirror image thereof.
